UNITED STATES PATENT OFFICE.

LEWIS G. ROWAND, OF CAMDEN, NEW JERSEY, ASSIGNOR TO HENRY C. TERRY, OF PHILADELPHIA, PENNSYLVANIA.

FIRE-ALARM SYSTEM.

SPECIFICATION forming part of Letters Patent No. 477,068, dated June 14, 1892.

Application filed December 14, 1891. Serial No. 415,053. (No model.)

To all whom it may concern:

Be it known that I, LEWIS G. ROWAND, a citizen of the United States, residing at Camden, New Jersey, have invented certain Improvements in Fire-Alarm Systems, of which the following is a specification.

My invention relates to certain improvements in that class of fire-alarm systems in which an alarm is sounded at a central station or other suitable point by the completion of a circuit by a thermostator switch or from some disarrangement of the circuit caused either by the grounding or breaking of one or other of the main or local lines in a building connected with the system, the arrangement of the system being such that different alarms are sounded from different causes and the recording of the alarms so sounded will distinguish an alarm of fire from an alarm caused by the breaking or grounding of one or other of the circuits.

In carrying out my invention I propose to place in the building one or more series of systems provided at suitable intervals with 25 thermostats or switches, the lines all terminating at a box or local station in the building, at which box the main-line wires are connected and which carries the alarms, local batteries, and connections, this box being preferably placed on the exterior of the building 30 for the convenience of the firemen, lineemen, and inspectors. In this box or local station is a series of instruments, hereinafter termed "mechanical signaling-alarms," which are 35 employed to sound different signals arising from different causes, and a series of annunciators are employed to show on what floor or circuit the alarm has been sounded from.

This system is especially arranged with a view of sounding an alarm of fire under various conditions of the wires or circuits, which may be enumerated as follows: first, with main outside line broken; second, with main outside line grounded; third, with main outside line short-circuited; fourth, with main outside line broken and grounded; fifth, with main outside line broken, grounded, and short-circuited; sixth, with main outside line grounded and short-circuited; seventh, with main outside line broken and short-circuited; eighth, with main inside line broken; ninth,

fifth, with main outside line broken and main inside line broken and building-line broken; thirty-sixth, with main outside line broken, main inside line short-circuited, and building-line short-circuited; thirty-seventh, with main outside line broken, main inside line broken and short-circuited, and building-line broken and short-circuited; thirty-eighth, with main outside line grounded, main inside line broken, and building-line broken; thirty-ninth, with main outside line grounded, main inside line short-circuited, and building-line short-circuited; forty, with main outside line grounded, main inside line broken and short-circuited, building-line broken and short-circuited; forty-first, with main outside line short-circuited and main inside line broken and building-line broken; forty-second, with main outside line short-circuited, main inside line short-circuited, and building-line short-circuited; forty-third, with main outside line short-circuited, main inside line broken and short-circuited, and building-line broken and short-circuited; forty-fourth, with main outside line broken and grounded, main inside line broken and building-line broken; forty-fifth, with main outside line grounded, main inside line short-circuited, building-line short-circuited; forty-sixth, main outside line broken, grounded and short-circuited, main inside line broken, and building-line broken; forty-eighth, main outside line broken, grounded, and short-circuited, main inside line short-circuited, building-line short-circuited; forty-ninth, main outside line broken, grounded, and short-circuited, main inside line broken, and building-line broken; fifty-first, main outside line grounded and short-circuited, main inside line broken and short-circuited, and building-line broken and short-circuited; fifty-second, main outside line grounded and short-circuited, main inside line short-circuited, building-line short-circuited; fifty-third, main outside line broken and short-circuited, main inside line broken, building-line broken; fifty-fourth, main outside line broken and short-circuited, main inside line short-circuited, building-line short-circuited; fifty-fifth, main outside line broken and short-circuited, main inside line broken and short-circuited, building-line broken and short-circuited; fifty-sixth, main inside line broken, building-line broken; fifty-seventh, main outside line broken, building-line short-circuited; fifty-eighth, main inside line broken, building-line broken and short-circuited; fifty-ninth, main inside line short-circuited, building-line broken; sixtieth, main inside line short-circuited, building-line short-circuited; sixty-first, main inside line short-circuited, building-line broken and short-circuited; sixty-second,

ond, main inside line broken and short-circuited, building-line broken; sixty-third, main inside line broken and short-circuited, building-line short-circuited; sixty-fourth, main inside line broken and short-circuited, building-line broken and short-circuited; sixty-fifth, main outside line broken, building-line broken; sixty-sixth, main outside line broken, building-line short-circuited; sixty-seventh, main outside line broken, building-line broken and short-circuited; sixty-eighth, main outside line grounded, building-line broken; sixty-ninth, main outside line grounded, building-line short-circuited; seventieth, main outside line grounded, building-line broken and short-circuited; seventy-first, main outside line short-circuited, building-line broken; seventy-second, main outside line short-circuited, building-line short-circuited; seventy-third, main outside line short-circuited, building-line broken and short-circuited; seventy-fourth, main outside line broken and grounded, building-line broken; seventy-fifth, main outside line broken and grounded, building-line short-circuited; seventy-sixth, main outside line broken and grounded, building-line broken and short-circuited; seventy-seventh, main outside line broken, grounded, and short-circuited, building-line broken; seventy-eighth, main outside line broken, grounded, and short-circuited, building-line short-circuited; seventy-ninth, main outside line broken, grounded, and short-circuited, building-line broken and short-circuited; eighty-first, main outside line grounded and short-circuited, building-line short-circuited; eighty-second, main outside line grounded and short-circuited, building-line broken and short-circuited; eighty-third, main outside line broken and short-circuited, building-line broken; eighty-fourth, main outside line broken and short-circuited, building-line short-circuited; eighty-fifth, main outside line broken and short-circuited, building-line broken.

In the accompanying drawings, Figure 1 represents a diagram of the house or building system, together with a diagram of the local station or box and the instruments employed for sending the alarm. Fig. 2 is a general diagram of the instruments employed at the central receiving-station. Fig. 3 is an elevation of one of the mechanical signaling-alarms. Fig. 4 is a longitudinal section of the same on the line xx , Fig. 5. Fig. 5 is an end view of the instrument, looking in the direction of the arrow, Fig. 3. Fig. 6 is a perspective view of a portion of the instrument. Figs. 7, 8, and 9 are detached views illustrating different positions of portions of the mechanical signaling-alarm. Figs. 10, 11, 12, 13, 14, and 15 are perspective views of different forms of circuit-breakers used on the mechanical signaling-alarms. Figs. 16, 17, 18, 19, 20, and 21 are diagrams illustrating the construction

of the circuit-breakers shown in Figs. 10, 11, 12, 13, 14, and 15, respectively. Fig. 22 is a plan view of the telegraph-key for communicating to the central station. Fig. 23 is a side view of the same. Fig. 24 is a plan view of the relay in the local station. Fig. 25 is a sectional view of the same on the line $y-y$, Fig. 24. Fig. 26 is a side view, partly in section, of one of the floor-annunciators. Fig. 27 is a view of a form of lightning-arrester which may be employed, and Fig. 28 is a sectional view of one form of thermostat which may be employed in carrying out my invention.

In the box or local station are placed three mechanical signaling-alarms of precisely similar construction, but provided with circuit-breakers of different character, as more fully described hereinafter. These alarms are for convenience marked 1, 2, and 3, respectively, in the diagram Fig. 1, and each has a train of gears, an electro-magnet normally preventing the movement of the same, and two circuit-breakers, as will be more clearly seen on reference to Figs. 3 to 21, inclusive. The construction of these alarms, however, forms the subject of a separate application for Letters Patent filed of even date herewith, Serial No. 415,054.

Figs. 3 to 9, inclusive, represent views of one of the mechanical signaling-alarms, which in the diagrams are designated, respectively, 1, 2, and 3, the construction of these alarms being identical, and the different uses to which they are put depending altogether on the construction of the circuit-breakers they carry. The circuit-breakers 4 and 5 (shown in Figs. 10 and 11) are carried by the alarm 1, the circuit-breakers 6 and 7, Figs. 12 and 13, are carried by the alarm 2, and the circuit-breakers 8 and 9, Figs. 4 and 5, are carried by the alarm 3, as shown in diagram Fig. 1.

10 10 are suitable side plates, in which are journaled the shafts of the train of gears which 45 actuate the mechanical alarm, 11 representing the main or primary shaft, which carries a spring 12 and a gear-wheel 13, the teeth of which mesh with the teeth of a gear-wheel 14, the shaft 15 of which extends outside the 50 frame-work and carries one or other of the circuit-breakers 5, 7, or 9. The gear-wheel 13 also serves to impart a rotative motion at a greater speed to a shaft 16 through the medium of a pinion 17, the shaft 16 being rotated 55 four times while the shaft 15 is rotated once.

The shaft 16 extends outside the frame-work and carries one or other of the circuit-breakers 4, 6, or 8. (Illustrated, respectively, in Figs. 10, 12, and 14.) On a shaft 18 is mounted a pinion engaging with the teeth of a wheel on the shaft 16, and also mounted upon this shaft is an escapement-wheel 19, with which engages an ordinary form of escapement 20, fixed upon a shaft 21, on which is also carried the governing-fan 22.

The gear-wheel 14, which is mounted upon the shaft 15, is provided, preferably on its op-

posite faces, with disks 23 and 24, in which are cut notches 25 26, the notch 25 in the disk 23 being at an angle of about ninety-two degrees from the notch 26 in the disk 24. 7c

Suitably mounted in the frame-work is a shaft 27, on which is carried a lever 28, provided at its lower end with an armature 29 under the control of an electro-magnet 30, 75 the upper end of the lever 28 being normally in engagement with one of the wings of the governing-fan 22 and acting through the fan to prevent the movement of the train of gears. On this shaft 27 is likewise secured an arm 31, the upper end of which is normally in engagement with the notch 25 in the disk 23 and being held in engagement therewith by a spring 32, extending from the lower end of the lever 28 to a fixed point on the frame, the 80 tension of the spring being adjusted by any suitable mechanism.

On a shaft 33, extending between the opposite sides of the frame, is mounted a lever 34, one end of which is provided with a toe 90 35, normally pressed against the periphery of the disk 24, and held in contact therewith by a spring 36, the tension of which may be adjusted. This toe 35 is adapted to enter into engagement with the groove or notch 95 26 in the disk 24.

The various circuit-breakers shown in Figs. 10 to 15, inclusive, are secured to the projecting shafts 15 16 of the mechanical signaling-alarms, two circuit-breakers being used on 100 each alarm. To suitable insulated blocks 37 38 are secured contact-brushes, which bear upon the circuit-breakers, to which the various line-wires are connected and through which the circuits are alternately made and 105 broken in sending signal-alarms.

Referring now to the diagram Fig. 1, 39 represents the thermostats or switches, which are placed at suitable intervals throughout the building, the series of thermostats or 110 switches on each floor being preferably in one circuit, and any number of circuits for different floors may be used, although for convenience I have illustrated but three in the diagram Fig. 1. 115

In the diagram Fig. 1 the heavy straight lines indicate the main line, through which the current is constantly passing, the direction of the current being indicated by arrows for the sake of convenience, although the direction of current may of course be reverse, if required. The building-circuits are indicated by straight lines, the ground-wires are indicated by heavy waved lines, and the testing-lines for testing the circuit are indicated in light waved lines. 120 125

40 is the main outside line, leading from the central station to the lightning-arrester 41 in the box or local station.

42 indicates the main inside line, extending 130 through the box and building to be protected.

43 is a shunt on the main circuit running to an electro-magnet on that one of the mechanical alarms employed for sending an

alarm in case of a broken wire in the main inside line. 44 is a branch of the main circuit, which is used when telegraphing to the central station, the operation of the telegraph-key causing the short-circuiting of the main inside line, so that the current passes through the branch 44 to the key and from thence by a ground-line 45 to the earth.

The general arrangement of the main inside line in the building is such that it parallels the house-line of each floor and is in electrical contact with one of the terminals of each thermostat or switch 39. The house-lines on the various floors form in themselves complete circuits extending from terminal to terminal of the various thermostats or switches, and the circuit being normally closed through a switch 46 and a contact-point 47. The switch 46 may be in the form of a spring the tendency 20 of which is to keep it at all times in contact with the contact-point 47 and maintain normally a closed circuit for each floor.

When one of the house-lines or one of the building-lines is grounded accidentally, the 25 alarm 1 is operated. In sounding the alarm of fire the alarm 1 is first operated, and this is followed by the operation of the alarm 2; but when one of the main inside lines is broken the alarm 3 only is operated.

30 In following out the house-circuit from the first floor through the alarms, 48 represents a wire extending from the contact-point 47 to the helix of an electro-magnet 48^a of an annunciator, preferably of the character illustrated in Fig. 26, and thence extends to one of the contact-brushes marked 49. Thence the circuit is established through the conducting portion of the circuit-breaker 6, through a brush 50, to a wire 51, which passes 35 from thence to a switch-lever 52, normally in contact with a contact-piece 53 and provided with a wire 54, extending to a brush 55, which is at all times in electrical contact with the conducting-surface of the circuit-breaker 5. (Illustrated in Figs. 11 and 17.) The circuit is 40 continued through a brush 56 and a wire 57 to an electro-magnet 30, which controls the mechanical alarm 1. From the electro-magnet 30 the circuit extends to a battery 58, preferably located in the box in which all of the instruments are placed, and from thence passes to the ground-wire 59, leading to the main ground-wire 45. The circuit of the second 45 floor is formed by a wire 60, extending from its contact-point 47 through the helix of an electro-magnet 48^b of its annunciator to a brush 61 on the circuit breaker 6, the circuit being through the circuit-breaker and the brush 50 to the electro-magnet 30 of the mechanical alarm 60 1 and the wire 51, as previously described. The circuit of the third floor is through the wire 62, through the helix of its electro-magnet 48^c of the annunciator and a brush 63, through the brush 50, and from thence through 65 the wire 51, as before described. These comprise the circuits, which are normally closed and which when brought into contact with

the main inside wire 42, constantly in circuit, will cause the energizing of the annunciator-magnet in the proper circuit and the energizing of the controlling-magnets 30 of the mechanical alarms 1 and 2.

The energizing of the electro-magnet 30 of the mechanical signaling-alarm 2 will (refer- 70 ring to Figs. 3, 4, 5, and 6) cause the attraction of the armature 29 and will move the lever 28 in the direction of the arrow, Fig. 6, and the movement of the arm 31 in the same direction, the lever 28 being moved from contact with the governing-fan 22 and the arm 31 80 being moved out of engagement with the notch 25 in the disk 23. The release of these parts will permit the spring 12 to move the train of gears and will effect the movement of the circuit-breakers in the direction of the arrow, 85 Fig. 3. The sounding of an alarm in this manner will first be described with reference to the mechanical signaling-alarm 1, since all the local connections of that alarm have been described. The main inside line connection 90 with this alarm is through contact-brushes 64, 65, 66, and 67, the brushes 64 65 being used on the lower side 68 of the circuit-breaker on the ingoing wire 42 and the brushes 66 67 being used on the upper side 69 of the circuit-breaker on the outgoing wire 42. The two 95 portions of the circuit-breaker are insulated from each other; but in rotating both parts come into electrical contact with a brush 70, connected to the ground-wire 59, so as to make 100 and break the circuit through the ground to the central receiving-station. The additional brushes 66 67 and the double circuit-breakers are used in case of the reversal of the current, which will be done under circumstances here- 105 inafter set forth. The ground-wire brush 70, it will be observed, normally rests on an insulated portion 71 of the circuit-breaker 4, as shown. As previously described, the circuit-breakers 4, 6, and 8 are rotated four times at 110 each operation of the mechanical alarms, and as they rotate will cause the breaking and making of the circuit of the main inside line 42, the circuit being made and broken as many 115 times as it is required to signal the number by which the building is known at the central receiving-station. The present alarm is constructed to signal the number "42," and the circuit-breakers 4, 6, and 8 are therefore provided with a number of insulated portions 120 which break and make the circuit four times, rest, and then break and make the circuit twice, thus signaling the number "42." Considering now that one of the local building-lines—say on the first floor—be accidentally grounded, a circuit will be established through that floor-line, switch 46, wire 48, annunciator-magnet 48^a, brush 49, circuit-breaker 6, brush 50, wire 51, switch 52, wire 54, brush 55, circuit-breaker 5, brush 56, magnet 30, battery 58, to earth, resulting in the energizing of the magnets 48^a and 30, the release of the train of gears, and the consequent 125 rotation of the circuit-breaker 4. At the first 130

movement of the circuit-breaker 4 the brushes 64 67 pass into contact with the insulated portions of the circuit-breaker, and the brush 70 comes into contact with the metallic portion 5 thereof and makes a connection between the main inside line and the ground, causing the annunciator-shutter 72 at the receiving-station, Fig. 2, to fall and show the particular circuit on which the alarm is being sounded. This closing of the circuit also raises the tape into contact with the printing-disk of the usual printer 73, Fig. 2, and it remains in contact with the tape while the main circuit is broken by the passage of the insulated portions 10 of the circuit-breaker under the brushes 65 66, the circuit being broken four times, then twice, and then for a comparatively long time while the ground-line brush 70 is passing over the insulated portion 71, printing a long dash and indicating a "ground" on the house-line. The circuit-breaker 4 rotates four times and sounds the alarm, printing on the tape at the central receiving-station the number of the box four distinct times, and 15 between the numbers prints a long dash, signifying that the line is in trouble. While the circuit-breaker 4 is completing its four revolutions the circuit-breaker 5 has nearly completed one revolution, the rotation of the train of gears being stopped (when the metallic portion 74 of the circuit-breaker 5 comes into the same position as that previously occupied by the portion 75 of the circuit-breaker) by the engagement of the toe 35 of 20 the lever 34 with the groove or notch 26 of the disk 24. The position of the circuit-breaker is such that the circuit through the brushes 55 56 between the wires 54 and 57 is broken and the circuit is established between 25 the line 54 and the brush 55 through the portion 74 of the circuit-breaker, a brush 76, and a wire 77 to a brush 78, through the metallic surface of the circuit-breaker 7 to the brush 79, and from thence by the wire 80 through the 30 controlling-magnet 30 of the mechanical signaling-alarm 2, the circuit from thence passing to the wire 81 to the main ground-wire 45. After the mechanical signaling-alarm 1 has been operated by the grounding of the house-wire (the system being energized by the local batteries) the signal will stop at this point, for the electro-magnet 30 of the mechanical signaling-alarm 2 will not be energized, since in 35 the circuit extending between the circuit-breaker 5 and the circuit-breaker 7 there is no battery, the only means of energizing said circuit being by a connection with the main inside line. The energizing of this circuit, therefore, will only occur in case of an alarm of 40 fire, when the thermostat or switch has operated to connect the main inside line with one of the house-lines.

Coming now to the circuit-breaker 6, which is operated only in case of fire, the circuit-breaker proper is divided into three portions 45 82 83 84, the portion 82 being provided with contact-brushes 85 86 on the ingoing wire of

the main inside line 42 and acting to make and break the circuit through said line when rotated. The portion 83 is precisely the same 70 in construction as the portion 82, is insulated therefrom, and is provided with contact-brushes 87 88 on the main outgoing wire. The portion 84 of this circuit-breaker is comparatively broad and has a conducting-surface extending entirely around its circumference, on which bears the brush 50. This circuit-breaker receives the brushes 49, 61, and 63 of the first, second, and third floor circuits, respectively, and is made broad enough to 75 take in as many brushes as there are circuits in the system. On the surface of this portion of the circuit-breaker are blocks of insulating material, which act to break the circuit and sound the number of the building, 80 "42," the blocks being of the same character and in precisely the same positions with respect to the brushes as the blocks of insulating material on the portions 82 83. This portion 84 is likewise provided with stepped ribs of insulating material 89, 90, and 91, one rib being 85 used for each floor and being so placed on the circuit-breaker that if the fire-alarm be on the circuit of the first floor its brush 49 will cross the rib 89. If the alarm be on the second-floor circuit, the brush 61 of that circuit will cross both the ribs 89 and 90 and the circuit between the brush 61 and the brush 50 will be twice broken in addition to the number of breaks required in sounding the alarm. If the 90 alarm be on the third floor, the circuit between the brush 63 and the brush 50 will be broken three times by the ribs 89, 90, and 91.

The circuit-breaker 7 is so arranged that a circuit is always established from wire 77 and 95 a brush 78 to the conducting portion of the circuit-breaker 92, which projects from the main ring and on which rests the brush 79, connected to wire 80 and the helix of the electro-magnet 30 of the mechanical alarm 2; but 100 after the circuit has been energized and the train of gears released the first movement of circuit-breaker 7 breaks the connection between brushes 78 and 79 and establishes the circuit between the brush 78 and a brush 93, 105 (which had previously been resting upon a block of insulating material 94,) and thence through the wire 95 to the electro-magnets 96 of a stroke-gong 97, and from thence by wire 98 to the ground-wire 59. The bringing of 110 this gong into the circuit causes the sounding of the alarm in the local station, the number of the building, "42," being first struck, and this is followed by the number of the floor or circuit in which the fire has occurred. The 115 tape at the central station receives a corresponding number of marks, the length of the "floor-marks" depending on the width of the ribs 89, 90, and 91 and the length of time for which the circuit is broken. These ribs 120 are therefore preferably made as narrow as possible, and in practice it has been found desirable that the floor should be designated merely by dots on the tape.

In order to provide an alarm in the event of the breaking of the main line in the building, I employ the third mechanical signaling-alarm 3, which is connected with the main inside line 42 by a shunt-circuit 43, thence through the brush 99, brush 100, brush 101, and the brush 102 to the controlling-magnet 30 of the alarm 3, and from thence back again to the return-circuit of the main line. This magnet is of a resistance greater than the resistance of the entire building-circuit, so that the current will normally pass through the building-circuit in place of passing through the magnet. When the wire is broken, however, the current passes through the shunt and the electro-magnet 30 is energized and by attracting its armature causes the release of the train of gears which operate the circuit-breakers 8 and 9 and cause the making and breaking of the circuit between the brushes 99 and 100 the necessary number of times to sound the number of the station, "42," and after the number of the station to print a short dash on the tape by the passage of the brush 100 over the insulated portion 102, thus serving to indicate at the central station that the main line in the building is broken. After the circuit-breaker has rotated the necessary four times and the circuit-breaker 9 has completed a partial revolution the circuit is broken between the brushes 101 and 102, leading to the controlling-magnet and is established between the brush 101 and the brush 104, thus cutting out the magnet and keeping the line intact without the resistance of the magnet-coils. In the box or local station at the point where the main-line wires 40 enter is a relay (illustrated more clearly in Figs. 24 and 25) having two electro-magnets 105 and 106 of equal power, the electro-magnet 105 being on the ingoing wire and the electro-magnet 106 being on the outgoing wire of the main inside line. Between these electro-magnets is an armature-lever 107, pivoted at 108 and acted upon by springs 109, which, aided by the equal attraction of the electro-magnets 105 and 106, keep the armature-lever central. Leading from the pivot-point 108 is a line 110, extending to a switch-lever 111, and from thence passes a wire 112 to a brush 113 on the portion 75 of the circuit-breaker 5. The outer end of the armature-lever 107 is adapted to come into contact with either the contact-point 114 or 115 when attracted by either electro-magnet, so that in the event of the current of the main building-line being grounded the current will on entering and passing over the electro-magnet 105 of the relay pass from thence through the main inside line to the ground, so that while the current is cut off the helix of the electro-magnet 106 the electro-magnet 105 is energized, causing the attraction of the armature 107 of the relay in the direction of the arrow, and thus establishing a circuit through the wires 110 112 and the circuit-breaker 5, and from thence through

the wire 57 to the electro-magnet 30 of the alarm 1 to the battery 58 and ground. The controlling-magnet is energized, the mechanical signaling-alarm operated, and an alarm is sounded. The printer at the central station, however, will simply print the number of the building, "42", and will not print the long dash before the number, as is the case with a ground on the circuit on the house-line, as before described, this being due to the fact that the current passes from the brush 65 to the brush 66 and from thence through the main line 42 to the ground in the building which caused the sounding of the alarm, the narrow ring of insulating material being spanned by the brush 70 and the current passing through such brush to the building-ground as offering the least resistance. 85

In order to provide for the sounding of the alarm in the event of the breaking of the ingoing line and the consequent reversal at the central station of the current, the extra brushes 66 and 67 are provided, the current in this case passing up through the main line 42 in the opposite direction to that indicated by the arrows, and in the event of a fire the circuit being completed by a thermostat or switch 39 from the main line to the house-line on the upper floor and from thence passing out to the ground on the lines 51, 54, 57, and 59, as before described. The brushes 66 and 67 cause the establishment of the circuit and the alarm being sounded by the making and breaking of the contact between the brushes 66 and 67. 95

116 represents a strap-key for telegraphing and aiding in testing some of the lines, the key being connected to the ground-wire 45 and having immediately under its free or finger end two contact-points 117 118, connected by the wire 44 with the main inside line. 105

In operation the current passes over the wire 44 to the contact-points 117 118 and from thence when in contact with the key to the wire 45 to the ground. In operating this key for telegraphing to the main station it is necessary in order to prevent any action of the mechanical signaling-alarm 1 to open the switch-lever 111, breaking the connection between the wires 110 and 112. If this were not done, the grounding of the current by the key would cause the attraction of the armature 107 and the passage of the current through the armature, the wires 110 and 112 to the circuit-breaker 5, and the consequent operation of the alarm 1. This circuit is convenient for testing the mechanical alarm 1 and relay-contacts when necessary. In the event of the reversal of the current at the main station when the ingoing main line is broken, the magnet 106 of the relay will be acted upon in the same way as the magnet 105 in the action just described. 120

As previously described, the system is especially arranged with a view of sounding alarms of fire under various conditions of the circuits. That condition (hereinaabove num- 130

bered 49) in which the main outside line is broken, grounded, and short-circuited, the main inside line broken and short-circuited, and the local or building line broken and short-circuited presents the greatest number of disarrangements of the circuits under which an alarm can be sounded. The other conditions (numbered from 1 to 85, respectively) are other combinations of these disarrangements.

10 To describe, first, the sounding of an alarm with the incoming wire of the main outside line broken, this would present no difficulty, as in such an event the operator at the central station receives due notice of the fact and reverses the current through the wires by the employment of a second set of batteries and receiving-instruments, so that the current then passes into the building by the wire heretofore described as the "outgoing" wire.

15 In the event of the grounding of the main outside line the ground at the central station is thrown off and the ground on the line acts as the ground for the central station. The short-circuiting of the main outside line can-25 not prevent the sounding of an alarm, since when the line is grounded by an alarm of fire the current will naturally pass through the ground-line as offering less resistance than the return-wire of the main line. With the

20 main inside line broken after the mechanical alarm 3 has sounded the circuit is established through the shunt 43 and the resistance of the electro-magnet 30 of the mechanical signaling-alarm 3 is cut out. When the main in-30 side line is short-circuited at a point outside the box or local station, the result is practically the same as with the short-circuiting of the main outside line, the current seeking the ground as offering less resistance than

35 40 the return through the main inside line and the main outside line. When the building-line is broken, the current will travel in either direction from the break, according to the side of the break on which the thermostat or switch operated is located, the floor-circuits being at all times closed. The short-circuiting of the building-line will have no effect, as the building-line is at all times closed and is normally not energized. The system will

45 50 sound an alarm with any one or with any combination of any of these difficulties or disarrangements of any and all of the circuits which may occur.

The system is so arranged as to provide for its being tested from time to time, and in order to provide for this testing by the inspector from the box or local station I employ the switch-lever 52, by which a connection with the ground-line 59 may be made, the ground-line being connected to a contact-piece 119 for that purpose.

Supposing the lever 52 to have made contact with the ground-line, a circuit is partially established, as follows: from ground-wire 58 and battery 55 to switch-lever 52, through wire 51 to brush 50, and to all of the branches 49, 61, and 63 on the floor-circuits. Now if it be

desired to test the circuit on the first floor the switch-lever 46 is moved from the contact-point 47 of the first-floor circuit and is moved into contact with a contact-piece 120 and a circuit established through the house-line on the first floor down through the switch-lever 46, through the contact-piece 120 and a test-line 121 to a switch-lever 122 and a wire 123 to the battery, and from thence to the ground-wire 59, establishing a circuit which the battery energizes and causes the energizing of the electro-magnet 48^a and the consequent operation of its annunciator.

If the system of the second floor is to be tested, the current passes, as before, through the ground-wire 59, the contact-piece 119, the switch-lever 52, the wire 51, the brush 50, the metallic surface of the circuit-breaker, the brush 61, the wire 60, the electro-magnet 48^b, the contact-piece 47, through the second-floor circuit, and from thence down through its switch-lever 46 to a contact-piece 124, to the test-wire 121, leading to the switch-lever 122, the wire 123, and from thence to the battery and the ground-wire 59. In the event of a break in the house-line the circuit will not be completed and the magnet of the armature will not be energized, the inspector receiving notice by that means of a broken wire in that particular circuit, and if all of the magnets fail to operate it will indicate that the battery has failed or that the connection from the battery to the test-line is broken. The connections leading to the third or other floors are exactly the same as those described for the first and second floors.

If it be desired to test the system and the mechanical signaling-alarms with a view of ascertaining that the circuits and alarms are in operative order, the switch-lever 122 is moved into contact with a contact-piece 125, establishing a circuit from the main line 42 through the contact-piece 125 and from thence through the testing-line 121 to the contact-piece 120 or the contact-piece 124 or other contact-piece on any one of the floor-circuits from which a circuit can be established to the floors, and by moving one or other of the levers 46 the circuit is established from the main line directly through the house-line and from thence through one or other of the wires 48, 60, or 62, and from thence passing through the system to sound an alarm, as before described.

If it be desired to test only the mechanical signaling-alarm 1, the contact is made only for a sufficient length of time to set that instrument into operation, and the circuit is then broken, and as there is no battery or energizing force on the circuit between the alarm 1 and the alarm 2 the alarm 2 will not be operated unless the testing-switches are held closed for a sufficient length of time to operate this instrument 2 also.

In Fig. 26 I have shown a form of annunciator which may be used, it consisting simply of an electro-magnet and an armature 126,

having a projecting toe 127, which is normally in engagement with an arm 128 on a weighted shutter 129.

Fig. 27 shows an ordinary form of lightning-arrester which may be employed, and Fig. 28 illustrates a sectional view of a thermostat which I may employ in carrying out my invention, although any ordinary or well-known form of thermostat or switch may be employed.

Referring now to Fig. 2, which represents the instruments commonly employed at the central station, the ingoing wire 42 to the central station passes through one side of a lightning-arrester and switchboard 130, from thence to a resistance-coil 131, a contact-point 132, an armature-lever 133, from thence to the main wire 42, to the main battery 133^a, to a strap-key 134, through relay-magnets 135, through an "ammeter" 136 for indicating the strength of the current, and from thence out through the lightning-arrester and switchboard 130 to the system in which is the building to be protected. When an alarm of fire or trouble from a building comes in, the current is directed from the outgoing wire of the central station through the mechanical signaling alarm or alarms at the local station and from thence to the ground, from the ground through the lightning-arrester and switchboard 130 to the wire 59, through a switch-lever 137, and from thence through electro-magnet 138 on the annunciator to the main wire 42, leading to the main battery. The energizing of this electro-magnet will cause the shutter 72 of the annunciator to fall, indicating the circuit in which the alarm has been sounded, and the annunciator is provided with an arm 139, which when the shutter falls presses against the armature 133 and breaks the contact between the contact-point 132 and the armature-lever 133 until the trouble in that circuit has been attended to. The construction of this annunciator, however, forms the subject of a separate application for patent, filed of even date herewith, Serial No. 415,056. The completing of the circuit through the wires 59 and 42 and the relay-magnets 135 causes the attraction at all times of the armature 140 of the relay. When, however, this circuit is broken by the making and breaking of the circuit by one of the mechanical alarms in the building, the armature-lever 140 is released from the control of the relay-magnets 135 and is then operated upon by a spring 141, which moves it into contact with a contact-point 142, the length of time for which it remains in contact with the contact-point 142 depending on the length of time for which the circuit is broken, while the continuous making and breaking of the circuit at predetermined intervals of time depends on the space between the insulated portions and the metallic portions of the circuit-breaker 4, 6, and 8, which cause a corresponding movement of the armature-lever 140. This movement causes the closing

and opening of a circuit from a local battery 143 through a wire 144, a switch-lever 145, and a wire 146, leading from one end of the armature-lever 140, through the electro-magnets 147 of a stroke-gong to the printing-register 73, the electro-magnets of the register being energized for the same length of time as the main line is broken and the alarm printed on the tape. If the incoming line to the central station is broken, the magnets 135 of the relay are not energized, and the armature-lever 140 then rests normally against the contact-point 142, the main circuit in this case traveling from the main battery out through the relay and ammeter to the break and remaining open until it is closed by the operation of one of the mechanical alarms, which causes the grounding of the main circuit and completes the circuit through the relay, energizing the magnets of the relay and causing the attraction of the armature 140 to a contact-point 148. In this event the switch-lever 145 is thrown over to a contact-point 149 and the local circuit from the battery 143 remains normally open until it is closed by the contact of the armature-lever 140 with the contact-point 142, causing the closing of the circuit and the consequent operation of the printing-register 73.

Throughout the specification and claims the term "main line" or "main outside line" is used to designate that line extending from the box or local station to the central receiving-station. The term "main inside line" or "main building-line" is used to designate the main-line wire or wires connected normally to the main outside wire at the box or local station and extending therefrom through the building. The term "building-line" or "local line" is used to designate those circuits connecting the thermostats, the annunciators, and circuit-breakers and indicated in light lines in the drawings. The term "test-line" has been used to designate those lines which are energized from the battery when it is desired to test portions of the local line, and the term "ground-line" is used to designate those lines shown as extending from the various instruments to the earth and illustrated by heavy waved lines in the drawings.

Details of construction may be varied—as, for instance, in the forms of switches, alarms, and other instruments.

By the term "circuit-breaker" I wish to include anything in the nature of a wheel or disk.

In applications filed of even date herewith, Serial Nos. 415,054 and 415,055, I have described and claimed the features of construction of the mechanical signaling-alarms and the circuits of the relay-magnets.

Having thus described my invention, I claim and desire to secure by Letters Patent—

1. In an electric fire-alarm system, the combination of the receiving-station and its instruments, the main line extending therefrom

to the local station and through the building, the building-circuits, a thermostat or switch normally open and having one of its ends connected to the main line and its opposite end connected to the building-circuit, a mechanical signaling-alarm operating a circuit-breaker, said mechanical signaling-alarm being normally locked, an electro-magnet in the building-circuit controlling the locking devices of said mechanical signaling-alarm, a second circuit-breaker, mechanism for rotating the same, an electro-magnet normally locking such mechanism, a normally-open circuit in which said electro-magnet is placed, said normally-open circuit being adapted to be closed by the mechanical signaling-alarm, and a ground connection normally out of circuit with the second circuit-breaker, but adapted to make circuit therewith, substantially as specified.

2. In an electric fire-alarm system, the combination of the receiving-station and its instruments, the main line extending therefrom to the local station and through the building, the building-circuits, a thermostat or switch normally open and connected to the main line and to the building-circuit, a mechanical signaling-alarm carrying a circuit-breaker, said mechanical signaling-alarm being normally locked, an electro-magnet in the building-circuit controlling the locking devices of said mechanical signaling-alarm, and a second circuit-breaker operated by the mechanical signaling-alarm and normally connected to the main line, substantially as specified.

3. In an electric fire-alarm system, the combination of the receiving-station and its instruments, the main line extending therefrom to the local station and through the building, the building-circuits, brushes thereon in electrical contact with a circuit-breaker 5, the circuit-breaker 5, a mechanical signaling-alarm carrying said circuit-breaker 5, an armature-lever controlling the rotation of the same, an electro-magnet in the building-circuit controlling said armature-lever, a circuit-breaker 4, contact-brushes on the main line in contact with said circuit-breaker 4, and a means of indicating a ground on the main inside line, comprising, in connection with the aforementioned mechanical signaling-alarm and its circuit-breakers 4 and 5, a relay-magnet 105 on the ingoing wire of the main inside line, a relay-magnet 106 on the outgoing wire of said line, an armature-lever mounted between said magnets and normally acted upon by said magnets with equal force, a branch of the main line extending from said armature-lever to the circuit-breaker 5, a contact-point 114, and a contact-point 115 on the main line, whereby on the grounding of the current at a point on the main inside line the current is diverted to the ground, substantially as specified.

4. In an electric fire-alarm system, the combination of the receiving-station and its instruments, the main line extending therefrom

to the local station and through the building, the building-circuits, brushes thereon in electrical contact with a circuit-breaker 5, the circuit-breaker 5, a mechanical signaling-alarm carrying said circuit-breaker 5, an armature-lever controlling the rotation of said circuit-breaker 5, an electro-magnet in the building-circuit controlling said armature-lever, a circuit-breaker 4, and contact-brushes on the main line in contact with said circuit-breaker 4, substantially as specified.

5. In an electric fire-alarm system, the combination of the receiving-station and its instruments, the main line extending therefrom to the local station and through the building, the building-circuit, a thermostat or switch adapted to connect the main line to the building-circuit, a circuit-breaker 6, mechanism for rotating the same, brushes in contact with said circuit-breaker, the building-circuits electrically connected to said brushes, circuit-breaker 5, mechanism for revolving the same, a brush 55 in contact with said circuit-breaker 50 and electrically connected to a brush 50 in contact with the circuit-breaker 6, an electro-magnet in a circuit of which a brush 56 in contact with the circuit-breaker 5, forms a terminal, a battery in the magnet-circuit, the circuit-breaker 4, brushes electrically connected to the main inside line and in contact with said circuit-breaker, a brush 76, normally in contact with the insulated portion of the circuit-breaker 5 an electro-magnet in a circuit of which the brush 76 forms a terminal, said electro-magnet controlling the mechanism for revolving the circuit-breaker 6, and a conducting portion 74 on the circuit-breaker 5, which when brought into contact with the brush 76 serves to complete the circuit through the electro-magnet controlling the rotation of circuit-breaker 6, substantially as specified.

6. In an electric fire-alarm system, the combination of the receiving-station and its instruments, the main line extending therefrom to the local station and through the building, the building-circuits, thermostats or switches adapted to connect the main line to the building-circuits, a circuit-breaker 6, a series of brushes in contact therewith, one of said brushes being electrically connected to each building-circuit, stepped ribs of insulating material on said circuit-breaker 6, a contact-brush 50, mechanism for rotating the circuit-breaker 6, and an electro-magnet adapted to lock said mechanism, said electro-magnet being in a normally-open circuit extending from the brush 50 to the ground, with means for closing the circuit and energizing the said electro-magnet to effect the release of the mechanism, substantially as specified.

7. In an electric fire-alarm system, the combination of the receiving-station and its instruments, the main line extending therefrom to the local station and through the building, the building-circuit, thermostats or switches adapted to connect the main line to the building-circuit, annunciator-magnets on said

- building-circuits, a circuit-breaker 6, a series of brushes in contact therewith, said brushes being electrically connected to the building-circuit, stepped ribs of insulating material on 5 said circuit-breaker 6, a brush 50, normally in contact with said circuit-breaker, mechanism for rotating the circuit-breaker 6, and an electro-magnet normally acting to lock said mechanism, said magnet being in a normally-open 10 circuit extending from the brush 50 to the ground, with means for automatically closing the circuit and energizing the said magnet to effect the release of the mechanism, substantially as specified.
- 15 8. In an electric fire-alarm system, the combination of the receiving-station and its instruments, the main line extending therefrom to the local station and through the building, the building-circuits, thermostats or switches 20 adapted to connect the main line to the building-circuit, a circuit-breaker 6, a series of brushes in contact therewith, one of said brushes being electrically connected to each building-circuit, contact-brushes electrically 25 connected to the main line and in contact with the circuit-breaker, a contact-brush 50, mechanism for rotating the circuit-breaker 6, and an electro-magnet adapted to lock said mechanism, said electro-magnet being in a normally-open 30 circuit extending from the brush 50 to the ground, with means for closing the circuit and energizing said electro-magnet to effect the release of the mechanism, substantially as specified.
- 35 9. In an electric fire-alarm system, the combination of the receiving-station and its instruments, the main line extending therefrom to the local station and through the building and normally forming a closed circuit, a circuit-breaker 6, through which said circuit is 40 closed, means for rotating said circuit-breaker, and contact-brushes on the main line in electrical contact with the circuit-breaker 6, whereby on the rotation of the circuit-breaker 45 the circuit through the main line is alternately broken and made, substantially as specified.
10. In an electric fire-alarm system, the combination of a central receiving-station and its instruments, the main line extending therefrom to the local station and through the building, the building-circuits, thermostats or switches adapted to connect the main inside line to the building-circuits, a circuit-breaker 6, comprising rings 82, 83, and 84, insulated 50 from each other, alternate insulated and conducting portions on said circuit-breaker 6, contact-brushes on the main inside line in contact with said insulated portions 82 and 83, stepped ribs of insulating material on the portion 55 84 of said circuit-breaker, a series of brushes on the building-circuits in contact with said portion 84, a brush 50, mechanism for rotating said circuit-breaker 6, an electro-magnet controlling said mechanism, said electro-magnet being in a normally-open circuit 60 extending from the brush 50 to the ground, and means for automatically closing said cir-

cuit and energizing the said electro-magnet to effect the release of the mechanism, substantially as specified.

11. In a fire-alarm system, the combination of the receiving-station and its instruments, the main line extending therefrom to the local station and through the building, the local lines, a thermostat or switch between such local line and the main line, circuit-breakers 6 and 7, mechanism for rotating the same, contact-brushes on the main line in contact with said circuit-breaker 6, brushes on the local line in contact with said circuit-breaker 7, and an electro-magnetic bell, the conducting and insulating portion of the circuit-breaker 7 being so arranged that after the circuit-breakers have started their rotation the current will be directed through the circuit-breaker 7 to the electro-magnets of the bell, substantially as specified.

12. In an electric fire-alarm system, the combination of a receiving-station and its instruments, the main line extending therefrom to the local station and through the building, the local lines, a circuit-breaker 6, mechanism for rotating the same, an electro-magnet for controlling the movement of said mechanism, brushes on the local lines in electrical contact with the conducting-surface of the circuit-breaker 6, and a normally-open circuit extending from the circuit-breaker 6 through the electro-magnet to the earth, substantially as specified.

13. In an electric fire-alarm system, the combination of a receiving-station and its instruments, the main line extending therefrom to the local station and through the building, the circuit-breaker 6, the local lines, brushes on said local lines in electrical contact with the conducting-surface of said circuit-breaker 6, annunciator-magnets on said local lines, annunciator for the floor-circuits operated by said annunciator-magnets, mechanism for rotating said circuit-breaker 6, an electro-magnet controlling said mechanism, and a normally-open circuit extending from said circuit-breaker through the electro-magnet to the earth, substantially as specified.

14. In an electric fire-alarm system, the combination of a receiving-station and its instruments, the main line extending therefrom to the local station and through the building, the local lines, a circuit-breaker, mechanism for rotating the same, and an electro-magnet controlling said mechanism, said circuit-breaker having a series of ribs of insulating material stepped in length, with brushes on the local circuit under which said ribs pass, and a normally-open circuit extending from said circuit-breaker through the electro-magnet to the earth, substantially as specified.

15. In an electric fire-alarm system, the combination of a receiving-station and its instruments, the main line extending therefrom to the local station and through the building, a circuit-breaker in said local station, the main ingoing wire having its circuit completed

through one side of the conducting portions of the circuit-breaker and the main outgoing line having its circuit completed through the conducting portions of the opposite side of the circuit-breaker, and a ground-wire, and a brush on said ground-wire normally in contact with the insulated portion of said circuit-breaker and so arranged as to come into contact with both of the conducting portions of said circuit-breaker on the rotation of the latter, substantially as specified.

16. In an electric fire-alarm system, the combination of the central receiving-station and its instruments, the main line extending therefrom to the local station and through the building, a shunt on said main line, an electro-magnet of high resistance in said shunt, a mechanical signaling-alarm controlled by said resistance-magnet, and a circuit-breaker adapted to make and break the main-line circuit through the shunt, substantially as specified.

17. In an electric fire-alarm system, the combination of the receiving-station and its instruments, the main line extending therefrom to the local station and through the building, an electro-magnet, a shunt on said main line on which said electro-magnet is placed, a mechanical signaling-alarm controlled by said electro-magnet, and circuit-breakers carried by said mechanical alarm, the arrangement of conducting-surface of one of said circuit-breakers being such that after the electro-magnet has once been energized the current through said electro-magnet is cut off, substantially as specified.

18. In an electric fire-alarm system, the combination of a receiving-station and its instruments, the main line extending therefrom to one or more local stations, and a means of indicating a break in said main-line wire, comprising a shunt-circuit, an electro-magnet therein of a higher resistance than the resistance through the main line, a train of gears, an armature-lever under the control of said electro-magnet normally locking such train of gears, and a circuit-breaker carried by said train of gears, substantially as specified.

19. In an electric fire-alarm system, the combination of the receiving-station and its instruments, the main line extending therefrom to one or more local stations, and a means of indicating a break in said main-line wire, comprising a shunt-circuit, an electro-magnet therein of a higher resistance than the resistance of the main line, an armature-lever under the control of said magnet, a mechanical alarm normally locked by said armature-lever, and circuit-breakers carried by said mechanical alarm, one of said circuit-breakers being provided with alternate insulating and conducting portions and adapted to make and break the circuit through said shunt and main line and the other of said circuit-breakers being adapted to cut off the flow of current through the electro-magnet after it has once been energized, whereby the resistance of such mag-

net to the passage of the current is avoided, substantially as specified.

20. In an electric fire-alarm system, the combination of the main line, the local lines, a ground-wire, a local battery between such local lines and the ground-wire, and annunciators on said local lines with switches for connecting the local lines to the ground-wire and battery for the purpose of energizing the circuit, substantially as specified.

21. A fire-alarm system comprising the main line, the local lines forming closed circuits, thermostats or switches between such local lines and main line, annunciator-magnets on said local lines, a battery, and a test-line having contact-points extending to said battery, with switches for connecting the local lines to the contact-points of such test-line, substantially as specified.

22. In a fire-alarm system, the combination of the main line, the local lines, thermostats or switches between said main line and the local lines, a circuit-breaker 6, mechanism for rotating the same, an electro-magnet controlling said mechanism, contact-brushes on the local lines normally in contact with said circuit-breaker 6, the circuit-breakers 4 and 5, brushes on the main line in contact with said circuit-breaker 4, brushes on the local lines in contact with said circuit-breaker 5, mechanism for rotating said circuit-breakers 4 and 5, an electro-magnet controlling said mechanism, and a normally-open circuit extending from said circuit-breaker 6 through the electro-magnet to the ground, substantially as specified.

23. In a fire-alarm system, the combination of the main line extending from the central station through the building, the local lines, thermostats or switches between said main line and the local lines, a circuit-breaker 6, brushes on the local lines in contact with said circuit-breaker 6, mechanism for rotating said circuit-breaker, a circuit-breaker 4, brushes on the main line in contact with said circuit-breaker 4, mechanism for rotating the same, an electro-magnet controlling said mechanism, and a normally-open circuit extending from said circuit-breaker 6 through the electro-magnet to the earth, substantially as specified.

24. In an electric fire-alarm system, the combination of the main line extending from a receiving-station through the building, the local lines, thermostats or switches between said local lines and the main line, annunciator-magnets on said local lines, the circuit-breaker 6, brushes on the local lines in contact with said circuit-breaker 6, mechanism for rotating said circuit-breaker, a circuit-breaker 4, having insulated and conducting portions brushes on the main line in contact therewith, mechanism for rotating the said circuit-breaker 4, an electro-magnet controlling said mechanism, and a normally-open circuit extending from said circuit-breaker 6 through the electro-magnet to the earth, substantially as specified.

25. In an electric fire-alarm system, the combination of the receiving-station and its instruments, the main line extending therefrom to the local station and through the building, 5 the local lines, thermostats or switches between the said main line and the local lines, the circuit-breaker 6, having ribs of insulating material stepped in length, brushes on the local lines in contact with said circuit-breaker, 10 a circuit-breaker 4, brushes on the main line in contact therewith, mechanism for rotating said circuit-breaker 4, an electro-magnet controlling said mechanism, and a normally-open circuit extending from said circuit-breaker 6 15 through the electro-magnet to the earth, substantially as specified.

26. In an electric fire-alarm system, the combination of a receiving-station and its instruments, the main line extending therefrom to 20 the local station and through the building, the local lines, thermostats or switches between the said main line and the local lines, the circuit-breaker 6, having ribs of insulating material stepped in length, brushes on the local lines in contact with said circuit-breaker 6, a circuit-breaker 4, brushes on the main line in contact with said circuit-breaker 4, mechanism for rotating said circuit-breaker, an electro-magnet controlling said mechanism, 25 a normally-open circuit extending from said circuit-breaker 6 through the electro-magnet to the earth, and a battery on said normally-open circuit, substantially as specified.

27. In an electric fire-alarm system, the combination of a receiving-station and its instruments, the main line extending to a local station and through the building, local lines, thermostats or switches between said main line and the local lines, a circuit-breaker 6, 30 comprising insulated rings 82, 83, and 84, contact-brushes on the local lines in contact with the portion 84, a circuit-breaker 4, brushes on the main line in contact with said circuit-breaker 4, mechanism for rotating said circuit-breakers, an electro-magnet controlling said mechanism, a normally-open circuit extending from the portion 84 through the electro-magnet to the earth, and contact-brushes on the main line in contact with the portions 35 82 83 of the circuit-breaker 6, substantially as specified.

28. In an electric fire-alarm system, the combination of a receiving-station and its instruments, the main line extending to a local station and through the building, the local lines, thermostats or switches between said main line and the local lines, a circuit-breaker, a ring 84 thereon, mechanism for rotating the same, contact-brushes on the local lines in 40 contact with said ring 84, a circuit-breaker 4, brushes on the main line in contact with said circuit-breaker 4, a circuit-breaker 5, mechanism for rotating said circuit-breakers 4 and 5, an electro-magnet controlling said mechanism, a normally-open circuit extending from the portion 84 through brushes in contact 45

with the circuit-breaker 5 and from thence through the electro-magnet to the earth, an electro-magnet controlling the mechanism for rotating the ring 84, and a normally-open circuit extending from a brush 76, in contact with the insulated portion of said circuit-breaker 5, through the electro-magnet controlling the mechanism for rotating the portion 84 to the earth, and a conducting-surface 74 on the circuit-breaker 5, through which the circuit is completed on the stopping of the circuit-breaker, substantially as specified. 50

29. In an electric fire-alarm system, the combination of a receiving-station and its instruments, the main line extending to the local station and through the building, the local lines, thermostats or switches between said main line and the local lines, a circuit-breaker 6, a ring 84 thereon, mechanism for rotating the same, contact-brushes on the local lines in contact with said ring 84, a circuit-breaker 4, brushes on the main line in contact with said circuit-breaker 4, a circuit-breaker 5, mechanism for rotating said circuit-breakers 4 and 5, an electro-magnet controlling said mechanism, a normally-open circuit extending from the portion 84 through brushes 55 and 56 in contact with the circuit-breaker 5, and from thence through the electro-magnet to the earth, an electro-magnet controlling the mechanism for rotating the ring 84, and a normally-open circuit extending from a brush 76, in contact with the insulated portion of said circuit-breaker 5, through the electro-magnet controlling the mechanism for rotating the portion 84 to the earth, and a conducting-surface 74 on the circuit-breaker 5, through which the circuit is completed on the stopping of the circuit-breaker, the circuit-breaker 7, and the electro-magnet 96 of the electric bell 97, substantially as specified. 95

30. In an electric fire-alarm system, the combination of a receiving-station and its instruments, the main line extending to the local station and through the building, the local lines, thermostats or switches between said main line and the local lines, a circuit-breaker 6, a ring 84 thereon, mechanism for rotating the same, contact-brushes on the local lines in contact with said ring 84, a circuit-breaker 4, brushes on the main line in contact with said circuit-breaker 4, a circuit-breaker 5, mechanism for rotating said circuit-breakers 4 and 5, an electro-magnet for controlling said mechanism, a normally-open circuit extending from the portion 84 through brushes 55 and 56 in contact with the circuit-breaker 5, and from thence through the electro-magnet to the earth, an electro-magnet controlling the mechanism for rotating the ring 84, and a normally-open circuit extending from a brush 76, in contact with the insulated portion of said circuit-breaker 5, through the electro-magnet controlling the mechanism for rotating the portion 84 to the earth, and a conducting-surface 74 on the circuit-breaker 5, 100

- through which the circuit is completed on the stopping of the circuit-breaker and the portions 82 and 83 of the circuit-breaker 6, substantially as specified.
- 5 31. In an electric fire-alarm system, the combination of a receiving-station and its instruments, the main line extending to a local station and through the building, the local lines, thermostats or switches between said main line and the local lines, a circuit-breaker 6, a ring 84 thereon, mechanism for rotating the same, contact-brushes on the local lines in contact with said ring 84, a circuit-breaker 4, brushes on the main line in contact with said circuit-breaker 4, a circuit-breaker 5, mechanism for rotating said circuit-breakers 4 and 5, an electro-magnet controlling said mechanism, a normally-open circuit extending from the portion 84 through brushes 55 and 56 in contact with the circuit-breaker 5, and from

thence through the electro-magnet to the earth, an electro-magnet controlling the mechanism for rotating the ring 84, and a normally-open circuit extending from a brush 76, in contact with the insulated portion of said circuit-breaker 5, through the electro-magnet controlling the mechanism for rotating the portion 84 to the earth, and a conducting-surface 74 on the circuit-breaker 5, through which the circuit is completed on the stopping of the 30 circuit-breaker, and the annunciators on the local circuits, substantially as specified.

In testimony whereof I have signed my name to this specification in the presence of two subscribing witnesses.

LEWIS G. ROWAND.

Witnesses:

JNO. E. PARKER,
HARRY SMITH.
